UNITED STATES PATENT OFFICE

131,142

DESIGN FOR A DEEP SADDLE SEAT CUSHION

Harold W. Bostrem, Milwaukee, Wis.

Application August 3, 1940, Serial No. 94,212

Term of patent 14 years

To all whom it may concern:

Be it known that I, Harold W. Bostrom, a citizen of the United States, residing at 133 East Washington Street, in the city of Milwaukee and State of Wisconsin, have invented a new, original, and ornamental Design for a Deep Saddle Seat Cushion, of which the following is a specification, reference being had to the accompanying drawing, forming a part thereof.

Fig. 1 is a front perspective view of a deep saddle seat cushion showing my new design; and

Fig. 2 is a side perspective view of the cushion shown in Fig. 1.

I claim:

The ornamental design for a deep saddle seat cushion, as shown.

HAROLD W. BOSTROM.
